UNITED STATES PATENT OFFICE.

REMER Y. SCRUGGS, OF HAHIRA, GEORGIA.

PIPE THIMBLE.

Application filed February 16, 1923. Serial No. 9,581.

To all whom it may concern:

Be it known that I, REMER Y. SCRUGGS, a citizen of the United States, and a resident of Hahira, in the county of Lowndes and 5 State of Georgia, have invented a new and useful Improvement in Pipe Thimbles, of which the following is a specification.

This invention relates particularly to the curing of tobacco in which art the tobacco 10 plants are suspended in a barn-like structure and subjected to heat treatment to dry them out evenly to a given color to adapt it to the trade.

The flues commonly used are of stove pipe 15 iron which carries the products of combustion of a furnace, the high heat of which often damages the flues requiring renewal. I have discovered that the life of the flues may be greatly prolonged by connecting 20 them where the joint is made in the curing chamber with a metallic thimble firmly fixed, in a way I will describe, solidly in the masonry at one end of the furnace.

The thimble is preferably made of a sub- 25 stantial thickness to provide a liberal heat storage and of such a construction herein-after described as will prevent cracking the masonry wall. This thimble which is the cardinal essential of my invention is square 30 or rectangular in cross-section to adapt it to enter readily into the brick-work and at its free end is circular with a sloping wall to provide an easy fit of the stove pipe flue.

Although the invention is primarily 35 adapted to the art of curing tobacco, I desire to have it understood that it is applicable generally in the heating art, as my thimble may be of essential advantage wherever a flue joint is needed in a masonry wall to 40 conduct the products of combustion from a stove or furnace.

My pipe thimble is preferably made in the form of an iron casting about a quarter of an inch thick, hollow and square or rectangular 45 at one end and round with a taper at the other. The squared end is provided with a series of slots or slits by which the mortar may lock it firmly into the brick-work, the foraminous structure serving the additional 50 advantage of preventing cracking of the brick-work from uneven expansion.

The invention, however, is not limited to a heavy metallic structure as fairly advan- 55 tageous results may be secured by employing rolled metal such as Swedish iron. The invention, therefore comprises a tubular fur-

nace thimble square at one end with apertured sides, and tapering cylindrically at the other end to admit of ready junction with a stove pipe.

Referring now to the drawings:

Figure 1 shows an application of my invention to a curing chamber for tobacco;

Figure 2 shows an application of my thimble to masonry work; and

Figure 3 shows, in perspective, the structure of the thimble in detail.

These curing chambers especially as applied in the southern tobacco district are usually a barn-like structure, the walls of 70 which are formed of cheap timber accessible on a farm and provided with some cheap form of restricted ventilation; the tobacco plants are suspended on racks of wood distributed throughout the chamber. A furnace is let into one wall through a cement or brick-work opening and stoked with cheap fire-wood from the front, and the flues are taken within the chamber from the rear of the furnace and distributed through a rectangular 75 system of pipes of thin sheet iron carried a short distance from the walls, and connected by a vent through the wall at the front.

In Figure 1 the numeral 1 represents in 80 section a curing chamber of the kind described. 2 represents cheap furnace let through the walls with suitable fire protection not indicated. The furnace may be stoked from the front. Cheap form of fire- 85 wood available on a farm is commonly employed.

At the rear is let a central pipe 3 commonly made of sheet iron and connecting with a rectangular system 4' to distribute the hot products of combustion through the 90 chamber a short distance from its walls, as indicated in Figure 1. This is the ordinary 95 construction employed in the southern tobacco district. The life of the piping is

much prolonged, in fact is prolonged three 100 times by the employment of my invention. This is because the thin walls of the flues becoming highly heated at the furnace corrode; I find that it may be largely minimized by providing the joint with an efficient air-tight construction and by making it of sufficient section as not to rise to overheat. I 105 therefore preferably make my thimble 4 (Figures 2 and 3) of a substantial cross-section and make it of metal, preferably a hollow casting about a quarter of an inch thick. The forward end 5 is rectangular in

cross-section and cast with a plurality of oblong holes on each side as indicated at 6. When it is set with mortar into the masonry the square conformation makes a snug fit in the brick work and the mortar threads the holes and firmly locks the whole in place in the brick work. The free end 7 has a slight taper and is round in shape, as indicated.

While I prefer to form this of cast metal as described, far better results than ordinarily obtained will follow even if made of thin sheet metal, the essential prerequisite of which is that the structure shall be of a unitary character and preferably integral throughout, thus preventing accidental sep-

ration or rupture and assuring long life of hard usage.

Having thus fully described my invention, what I claim as new and desire to secure by Letters Patent is:

1. A pipe thimble for a furnace consisting of a tubular casting rectangular at one end with apertured sides, and a tubular cylindrical extension at the other end.

2. A pipe thimble consisting of a rectangular casing open at one end and having apertured sides, and a tapering tubular extension at its opposite end.

I hereto affix my signature.

REMER Y. SCRUGGS.
